UNITED STATES PATENT OFFICE.

RICHARD D. GALLAGHER, JR., OF NEW YORK, N. Y.

FRICITION DRAFT-GEAR FOR RAILWAY-CARS.

1,353,529.

Specification of Letters Patent. Patented Sept. 21, 1920.

Application filed November 20, 1915. Serial No. 62,551.

To all whom it may concern:

Be it known that I, RICHARD D. GALLAGHER, Jr., a citizen of the United States, residing at New York, in the county and State of New York, have invented certain new and useful Improvements in Friction Draft-Gears for Railway-Cars; and I do hereby declare the following to be a full, clear, and exact description of the same, reference being had to the accompanying drawings, forming part of this specification.

The objects of the present invention are primarily to provide a draft gear having an exceedingly high efficiency and at the same time a gear which will be within the dimensions fixed by standard practice. Another object is to provide a compact gearing in which the now well recognized benefits of friction members will be secured without complication of parts and without exceeding standard dimensions. Still other objects of the invention are to provide a gear in which the parts cannot be assembled in incorrect relation to each other, and in which the parts are of such form and construction as to prevent distortion and breakage under the most severe strains to which they will be subjected in commercial usage.

The invention consists in certain novel details of construction and combinations and arrangements of parts, all as will be herein-after described and pointed out particularly in the appended claims.

Referring to the accompanying drawings,

Figure 1 is a side elevation of a draft gear embodying the present improvements.

Fig. 2 is a plan view of the same;

Fig. 3 is a section in a plane indicated by the dotted line 3-3 of Fig. 4.

Fig. 4 is a section in a broken plane indicated by the line 4-4 in Fig. 3, with some of the springs removed.

Fig. 5 is a section on the line 5-5 of Fig. 2.

Fig. 6 is an elevation of the spring plate.

Fig. 7 is an elevation of the friction box.

Fig. 8 is a view looking at the outer face of one of the friction blocks.

Like characters of reference in the several figures indicate the same parts.

The draft gear of the present invention embodies in its construction certain features which are common to the draft gear illustrated in patents heretofore granted to this applicant and which have now gone into ex-

tensive public use; that is to say, there are relatively movable parts with friction elements interposed between them, said friction elements embodying longitudinally and transversely movable wedge blocks with a center wedge which, by co-operation with the wedge blocks, is given a differential movement with respect to the relatively movable members, so as to compress the springs to a greater degree than would be the case were they interposed directly between the relatively movable parts of the gear. The structure also embodies a spring barrel or housing for the springs and a friction box carried by said barrel with which the blocks co-operate for effecting the lateral movement of the blocks proportionately in accordance with their longitudinal movement.

In the accompanying drawings, the housing or, as is commonly termed in the art, the spring barrel is indicated generally by the reference letter A; the friction box, by the reference letter B; the follower, by the reference letter C; the wedges, by the reference letter D; and the center wedge by the reference letter E.

In accordance with the present invention, the so-called spring barrel is an integral structure of generally rectangular formation, preferably closed at one end by a bottom F and having at the other end a rectangular opening forming a seat or throat with inclined walls f for the reception of the rectangular stem or neck b of the friction box B. The friction box B is made of a composition best calculated to withstand bursting strains and to afford proper friction faces for co-operation with the wedge blocks as will be hereinafter described. The stem portion b of the box is fitted in the throat or opening of the barrel with a fair degree of accuracy whereby the parts will be seated firmly against one another and a union or connection is effected by means which will not weaken either of the parts, preferably by the formation of openings in the joints and extending partly into the faces of the throat and neck respectively. Such openings are drilled after the parts are seated, and are then filled by rivets or rods G which are subsequently headed or upset at the ends, as indicated at σ in Fig. 3, whereby they are held in place and in turn firmly lock the barrel and friction box together.

The barrel is designed for the reception

of a series of springs preferably arranged in sets of three, and each spring is mounted in a separate cell, chamber or compartment, the cells being formed by vertical and horizontal webs H which bridge between the walls of the spring barrel and extend from the bottom F forwardly throughout the major portion of the barrel itself. The intermediate or central portions of the webs 5 at the spring box end are cut away, however, to permit of the movement of the parts in compressing the springs under strains to which the gear is subjected. The webs themselves are preferably provided with 10 openings h therein and these openings are substantially in alignment with openings a in the external walls of the barrel. In addition to the openings a the walls of the barrel are provided with openings a' in the 15 narrower sides, thus providing for an effectual ventilation of the parts and providing openings through which the interior may be inspected. The exterior base of the barrel is provided with longitudinally extending 20 recesses and ribs a'' , some of which pass around the openings hereinbefore referred to, said ribs, together with the internal partitions H serving to effectually brace and strengthen the whole structure, whereby 25 it is rendered competent to resist any distortion or breakage strains to which it may be subjected in use. In Fig. 5, it will be seen that the webs or partitions H at their junctions are curved as is also the exterior wall 30 at the sides of the several cells, whereby cells or chambers are formed which will substantially fit and confine the several springs in their proper relative positions. At the same time the cellular construction, due to 35 this formation, increases the strength of the structure and permits of the employment of relatively thin walls, thereby materially reducing weight without sacrificing strength.

The provision of a cellular spring barrel 40 not only greatly strengthens the structure, but makes provision for the use of springs which are relatively long as compared to their diameter, thus providing for a greater spring capacity than would be possible in 45 any other structure of similar dimensions. The springs are indicated by the reference letter I , and it is obvious that there may be in each cell or chamber, inner and outer coils, said coils being preferably reversely 50 wound, and at the bottom of each cell, the ends of the spring are held in proper relative position by lugs i properly spaced and formed, as shown in Fig. 5, for coöperation with the ends of the springs. Where inner 55 and outer coils are employed, it is preferred that the inner coils shall be shorter than the outer coils whereby they act only after a partial compression of the outer coils, thus giving a soft preliminary action as has been 60 heretofore proposed in this art.

At the forward end of the barrel the springs abut against the inner face of a spring plate K preferably having lugs or projections k for holding the springs in proper relative position at their forward 70 ends, the portions of the spring plate intermediate the springs being cut away, as shown at K' , K'' , in Fig. 6, to prevent interference with the forwardly extending portions of the webs or cell walls of the barrel. 75

This spring plate K is designed to receive pressure from the center wedge E and in the preferred construction it is connected therewith. To effect the union, the center wedge E is provided with a stem l , rectangular in cross section, which passes through a correspondingly shaped opening at the center of the spring plate. Extending transversely through the stem l is a curved aperture adapted for the reception of a pin l' 80 which is driven into position after the parts are assembled, and the ends bent back against the inner face of the spring plate, thereby locking the parts together and at the same time preventing the accidental escape of the pin itself. The pin and the inner end of the stem are located within a recess k' formed centrally in the inner face of the spring plate, thereby preventing any possible interference with the springs, and 85 permitting the spring plate to present a plane face for coöperation with the springs. 90

The center wedge E and the inclined friction faces B' of the friction box B form between them wedge-shaped recesses in 100 which the inner ends or angles of the wedge blocks D are adapted to seat. The outer faces of the wedge blocks D are adapted to receive the inner face of the follower C , whereby movement of the follower toward 105 the barrel, or movement of the barrel toward the follower will cause the wedge blocks to travel inwardly and laterally, thereby imparting a differential longitudinal movement to the center wedge and proportionately compressing the springs. The wedge blocks D , while of generally triangular formation, as has heretofore been proposed in the art, are, in the present instance, cut away 110 at one corner, thereby forming faces d 115 which, when the wedge blocks are in position, are substantially parallel with the longitudinal center of the gear. In addition, each wedge block is formed with a recess or slot d' extending inwardly from the faces d and adapted for the entry of a tongue or projection c on the inner face of the follower C . 120

Inasmuch as the parts in the present structure are arranged in exceedingly compact 125 relation and it is desirable to make the tongue c as wide as possible, the outer corner of the center wedge E is slotted for the reception of the inner edge of the tongue, as shown clearly in Figs. 3 and 4 and as a 130

result of the arrangement it becomes impossible to assemble the parts in an incorrect relation to each other. Furthermore, by cutting away the proximate corners of the 5 triangular wedge blocks D, the said blocks are permitted to approach each other, or to have a more extended range of lateral movement than would be the case were true triangular blocks employed, thus materially 10 reducing the space required for their operation, and correspondingly reducing the size of the whole apparatus. The tongue e lying within the slot d' in the wedge blocks D prevents said wedge blocks from getting out 15 of alignment and may thus be said to perform the dual functions of strengthening the follower, preventing the assembling of the parts in any other than their correct positions and the preservation of the alignment 20 of the parts after they are assembled.

With a gear embodying the construction hereinbefore set forth, it is practical to make the same of a size which will conform to standard practice and permit of the gear 25 being mounted in standard attachments. At the same time it presents the capacity of an external formation which will fit the attachments or coöperating parts, such as the stops, yoke, draw bars or buffer beams of 30 practically any of the customary equipments now in use.

What is claimed is:

1. A draft gear embodying a spring barrel having a plurality of longitudinally arranged partitions therein forming a series 35 of independent spring cells, said partitions having their central portions at the forward ends cut away to form a working space for the spring plate, independent springs located in said cells, a spring plate against which the forward ends of the springs abut, a follower, and friction elements intermediate the follower and spring plate.

2. A draft gear embodying a spring barrel, a friction box mounted in position at one 45 end of the barrel, springs located within the barrel, and a center wedge held advanced by the springs, of wedge blocks coöperating

with the friction box and center wedge respectively, said wedge blocks having parallel proximate faces and a follower co-operating with the outer faces of the blocks. 50

3. A draft gear embodying a spring barrel, a friction box at one end of the spring barrel, springs within the barrel and a center wedge held advanced by the springs, in combination with wedge blocks having their proximate portions slotted, and a follower against which the outer faces of the wedge blocks abut, having an inwardly extending tongue located in the slots in the wedge blocks. 55

4. A draft gear embodying a spring barrel, a friction box at the open end of the spring barrel, springs, and center wedge held advanced by the springs, in combination with wedge blocks having parallel proximate faces formed with aligned slots and a follower with which the outer faces of the wedge blocks coöperate provided with 60 an inwardly extending tongue positioned to work in the slots formed in the wedge blocks whereby the wedge blocks are held in proper alignment and the assembling of the parts in incorrect relation is prevented. 65

5. In a device of the character described, the combination with a casing of a separate friction shell, said casing and shell having coöperable slots adapted to be longitudinally aligned when the casing and shell are 70 assembled, and keys disposed within said slots, said keys being placed under shear throughout their length upon tendency of the shell and casing to shift longitudinally 75 relatively to each other. 80

6. In a device of the character described, the combination with a casing having an opening at one end thereof, of a shell having one end thereof extended and fitting within said opening, the overlapping parts of said 85 shell and casing having opposed slots and keys extending lengthwise of said slots, each key being positioned partly within a slot of the casing and partly within an opposed slot of the shell. 90
